UNITED STATES PATENT OFFICE

2,497,178

ADJUSTABLE PREFORMING HEAD

Owen A. McNamee, Worcester, Mass., assignor to
The American Steel and Wire Company of New
Jersey, a corporation of New Jersey

Application November 2, 1948, Serial No. 57,850

12 Claims. (Cl. 57—55)

1

The invention relates to a preforming head for wire-stranding or cable-armoring machines.

The preforming of wires as they are laid around a core to form a strand or around an insulated conductor or cable to form an armor sheath thereon has long been common practice and various types of preforming heads have been devised. The ability to vary the radius and pitch of the helix to which the wires are preformed is highly desirable and this has led to the provision of adjustable preforming heads. One of those with which I am familiar utilizes a worm and worm-wheel drive for circumferentially adjusting one of the three or more bevel-edge plates mounted in spaced relation along the axis of the laying machine with bending rollers spaced circumferentially therearound, which constitute the usual preforming head, to the desired angular position relative to the other plates. This varies the radius of the helix. Screws are also provided for adjusting the plates axially to vary the pitch of the helix.

The construction of known adjustable preforming heads described above is bulky and limits the minimum axial spacing between the bending rolls journaled radially on the beveled edges of adjacent plates, as well as the minimum radial dimension of the head. The result is that adjustable heads of known types are adapted only for preforming wires on large cores and cannot be made for preforming fine wires laid over small cores. In addition, the worm and worm-wheel adjusting means tends to creep under vibration and frequent checking and resetting are necessary to maintain the desired adjustment. The mounting of the roll-supporting plates lacks rigidity, furthermore, and the adjustment becomes progressively less exact with wear of the parts.

I have invented an improved preforming head having novel means for adjusting the middle plate angularly relative to the others and positively locking it in position so as to maintain precisely the desired setting thereof despite vibration or wear. The adjusting means is extremely simple and compact so it may be incorporated in heads of small size thus making possible the use of adjustable heads for stranding fine wires about a small core. In a preferred embodiment of my improved head, I provide a middle plate composed of a disc having a ring rotatable therearound to support the bending rolls. The disc has a segment cut out therefrom and a block is mounted on the disc having opposite faces exposed in the cut-out. Adjusting screws threaded

through the ring engage said faces and serve to rotate the ring on the disc and hold it in adjusted position. The faces of the block are preferably inclined outwardly toward a radius from the center of the disc through the block. The head also includes two outer plates, fixed against rotation relative to the stranding machine, one on either side of the angularly adjustable plate. All the plates are adjustable axially, being secured to the spindle of the stranding machine by set screws.

A complete understanding of the invention may be obtained from the following detailed description and explanation which refer to the accompanying drawings illustrating a preferred embodiment. In the drawings,

Figure 1 is a side elevation of my improved preforming head, partly in axial vertical section;

Figure 2 is a front elevation of the angularly adjustable plate, i. e., the intermediate plate in Figure 1 partly broken away and with parts in section;

Figure 3 is a sectional view through the intermediate plate of the head taken along the line III—III of Figure 2; and

Figure 4 is a partial diagrammatic plan view showing the effect of the angular adjustability of the middle plate on the radius of the helix.

Referring now in detail to the drawings, the delivery end of the hollow spindle of a machine for laying wire around the core of a strand or a cable to be armored is indicated at 10. The preforming head of my invention, indicated generally at 11, comprises circular plates 12, 13 and 14 keyed on the spindle. The plates are adjustable axially of the spindle and are secured in their adjusted positions by set screws or other equivalent locking means (not shown). The plates have their edges beveled in the usual manner and are provided with bending rollers 15 spaced uniformly around the entire circumference thereof (only a few being shown in the drawings) which serve to preform the wires 16 into helices of the desired radius and pitch as they are laid about the core or cable and drawn through the closing die (not shown). The rollers 15 are journaled on radial stub shafts 15^a disposed normal to the beveled edges of the plates. The axial adjustment of the plates relative to each other permits the pitch of the helices to be varied as desired. To permit adjustment of the radius of the helices, it is necessary to turn the intermediate plate 13 on the spindle relative to the other plates and it is to means for accomplishing this that my invention relates in particular.

The plate 13 comprises a disc 17 and a ring 18 rotatable thereon. To facilitate rotation, the disc has a peripheral groove 19 and the ring carries anti-friction means such as balls 20 traveling in the groove which serves as a race. To accommodate the balls 20 the ring 18 is drilled radially at circumferentially spaced points and fitted with plugs 21 threaded into the resulting holes to hold the balls in place and permit the proper adjustment thereof.

As best shown in Figure 2, the disc 17 has a portion of its edge milled off to form a segmental cut-out 22. The cut-out is recessed centrally, as indicated at 23, to accommodate an abutment in the form of a pyramidal block 24 fitting snugly therein. The block has a stud 25 projecting from the base thereof which is received in a hole drilled centrally in the recess 23. The block 22 has two parallel sides coplanar with the faces of the discs 17 and two inclined faces 26. The shape of the block in elevation is substantially that of an isosceles triangle and it is disposed, as shown, with its base normal to a radius of the disc drawn through the vertex. This vertex 27 is slightly flattened and has sliding engagement with the inner periphery of the ring 18.

Adjusting screws 28 are threaded into tapped holes in the ring 18. These holes are at an angle to each other but are not exactly radial. The screws engage the sloping faces of the abutment or bearing block 24 and rigidly secure the ring 18 in predetermined angular relation to the disc 17. An adjustment of this relation may easily be made by backing off one screw and turning down the other. It will be understood that only a relatively limited range of angular adjustment is necessary. In order to indicate the exact angular relation of the disc and ring, I provide an arcuate scale 29 on the disc 17 graduated in degrees and an index 30 on the ring 18 cooperating therewith. It will be apparent that the desired adjustment of the ring relative to the disc may be made quickly and easily. When it has been made and both screws again turned firmly against the block 24, the assembly is positively held in adjusted relation against any possibility of shifting in service as a result of wear, vibration or the like.

The principal advantage of the invention is its simplicity of structure and the resulting compactness whereby the necessary parts may be designed for the smaller sizes of preforming heads for which adjusting means previously known are not adapted. The invention thus makes it possible to gain the benefit of adjustable preforming on small strands or armor for small cables. The invention also has the advantage that the angular adjustment of the intermediate plate may be made with great precision and maintained during service despite wear and vibration, as already pointed out.

The adjustable intermediate disc is mounted directly on the spindle of the stranding machine. This contributes to a rigid mounting. The full pitch of the helices along the spindle is available for seating the plate giving a large bearing surface which holds the adjustment even after wear has occurred. The ring is held firmly in correct position on the disc by the bearing balls which thus maintain the rollers rigidly in proper position yet permit easy adjustment. The triangular shape of the bearing block increases the exactness of adjustment beyond that ordinarily result-

ing from the use of screws. The angular relation of the screws causes them to lock against loosening under vibration.

Although I have illustrated and described only a preferred embodiment of the invention, it will be recognized that changes in the details and arrangement of the parts thereof may be made without departing from the principle of the invention or the scope of the appended claims.

10 I claim:

1. In a preforming head for a wire-stranding machine a generally circular plate adapted to be mounted on the spindle of the machine for supporting wire-bending rollers spaced about the periphery thereof, said plate comprising a central disc, a ring surrounding the disc and rotatable thereon, said disc having a segmental cut-out in its periphery, a block mounted on said disc having opposite lateral faces exposed in said cut-out, and adjusting screws threaded through said ring and adapted to engage said faces.

2. The apparatus defined by claim 1 characterized by said faces sloping outwardly toward a radius from the center of the disc through said block.

3. The apparatus defined by claim 1 characterized by said block having a surface slidably engaging the inner periphery of said ring.

4. The apparatus defined by claim 1 characterized by said disc having a recess in said cut-out, said block fitting snugly in said recess.

5. The apparatus defined by claim 1 characterized by one of said disc and ring having a peripheral race, and anti-friction means carried by the other and adapted to travel on said race.

6. The apparatus defined by claim 1 characterized by said block having the shape in side elevation of an isosceles triangle and having its base normal to a radius of the disc drawn through the vertex of the block.

7. In a preforming head for a wire-stranding machine, a generally circular plate adapted to be mounted on the spindle of the machine for supporting wire-bending rollers spaced about the periphery thereof, said plate comprising a central disc, a ring surrounding the disc and rotatable thereon, a pair of adjusting screws extending through the ring at an angle to each other, and an abutment on said disc adapted to be engaged by both said screws.

8. The apparatus defined by claim 7 characterized by said abutment having oppositely sloping faces generally normal to said screws and adapted to be engaged thereby.

9. The apparatus defined by claim 7 characterized by said abutment being separate from the disc and said disc being cut out to receive the abutment.

10. The apparatus defined by claim 9 characterized by said abutment having a stud projecting inwardly therefrom, said disc having a hole therein to receive said stud.

11. The apparatus defined by claim 7 characterized by said abutment being of triangular shape in side elevation and disposed with its base generally normal to the radius of the disc drawn through the vertex of the abutment.

12. The apparatus defined by claim 7 characterized by anti-friction means carried by one of said disc and ring and a circumferential race in the other with which said means cooperate.

OWEN A. McNAMEE.
